(57) CLAIM

The ornamental design for a bottom wear, as shown and described.

DESCRIPTION

FIG. 1 is a perspective view of a bottom wear pad of a bottom wear showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along the line 8-8 of FIG. 2;

FIG. 9 is a perspective view of the bottom wear;

FIG. 10 is a cross-sectional view thereof taken along the line 10-10 of FIG. 9;

FIG. 11 is a cross-sectional view thereof taken along the line 11-11 of FIG. 9;

FIG. 12 is another perspective view of the bottom wear;

FIG. 13 is a cross-sectional view thereof taken along the line 13-13 of FIG. 12; and,

FIG. 14 is a cross-sectional view thereof taken along the line 14-14 of FIG. 12.

The broken lines in the drawings are for the purpose of illustrating portions of the bottom wear that form no part of the claimed design. The dot-dash broken lines in FIG. 9 represent unclaimed boundary lines and form no part of the claimed design.

1 Claim, 9 Drawing Sheets
